CLAIM

The ornamental design of a control module for a computer peripheral such as a media autochanger, as shown and described.

DESCRIPTION

FIG. 1 is a top, rear perspective view of a first embodiment of a control module for a computer peripheral such as a media autochanger showing our new design;

FIG. 2 is a top, left perspective view thereof;

FIG. 3 is a top plan view thereof;

FIG. 4 is a front elevation view thereof;

FIG. 5 is a rear elevation view thereof;

FIG. 6 is a right elevation view thereof of which the left elevation view is a mirror image;

FIG. 7 is a top, rear perspective view of a second embodiment of a control module for a computer peripheral such as a media autochanger showing our new design;

FIG. 8 is a top, left perspective view of said second embodiment; and

FIG. 9 is a top plan view of said second embodiment; and,

FIG. 10 is a side elevation view of said second embodiment.
